UNITED STATES PATENT OFFICE.

JOSEPH CHARLES EUGÈNE MATHIEU, OF NEUILLY, FRANCE.

MECHANISM FOR THE ALTERATION OF SPEED.

SPECIFICATION forming part of Letters Patent No. 664,961, dated January 1, 1901.

Application filed April 17, 1900. Serial No. 13,252. (No model.)

To all whom it may concern:

Be it known that I, JOSEPH CHARLES EU-
GÈNE MATHIEU, a citizen of the French Re-
public, residing at 209ter Avenue de Neuilly,
5 Neuilly, department of the Seine, France,
have invented a new and useful Improvement
in Mechanism for the Alteration of Speed, of
which the following is a specification.

My invention has for its object the construc-
10 tion of a mechanism for the alteration of speed
especially applicable to motor-cars, being a
particular combination of toothed driving
gear and belting. In the first place it must
be observed that one of the important fea-
15 tures of motor-car motion consists in provid-
ing the possibility of riding at various high
speeds; but if belt-driving is exclusively used
for the purpose the operator is practically re-
stricted to a very limited number of changes
20 of speed on account of the encumbrances and
complications inherent in this mechanism.
If only one belt is employed and motion is
transmitted to the driving-wheels of the car
by means of sprocket-wheel and chain-pinion,
25 it may sometimes be possible, especially in
the country, to get down from the car and to
alter the sprocket-wheel and chain-pinion in
order to obtain an alteration of speed suitable
30 to the change of gradient; but that will not be
feasible in town. This being stated, my inven-
tion contemplates the use of a certain num-
ber of trains of speed-reducing gear, thus pro-
ducing a corresponding number of different
35 main speeds, the reversed motion included—
in fact, being the usual contrivance for al-
tering speed by means of gearing—and at
the same time I combine this contrivance
with a belt arrangement for changing speed
40 in such a manner that for each reduced ve-
locity by gearing I obtain as many different
speeds as there are belts. If, for example,
three trains of speed-reducing gear are em-
ployed and two sets of belt-gear are combined
45 with the same, it becomes possible to alter the
motion of the car so as to run at six different
speeds, and in case four gearings and three
sets of belt-gear are used twelve different
speeds could be obtained; but of course it
50 must be understood that the relation between
the parts of the mechanism is of such a kind
that the speed resulting from one combina-
tion of gearing and belting is not the same as

that resulting from the combination of an-
other gearing and another set of belt-gear.
In fact, suppose a motor-car has three dif-
ferential gearings—viz., one of great reduc-
tion, one of smaller reduction, and one for
reverse motion—and in addition is fitted with
two sets of belt-gear for altering speed in the
proportion of one to one and one-half. Now 55
by combining the first belt and the first
toothed gearing a velocity of ten kilometers
(six and one-fourth miles) per hour is ob-
tained and by combining the second toothed
gearing and the first belt a speed of twenty 60
kilometers (twelve and one-half miles) is in-
sured. If, however, the second belt is com-
bined with the first toothed gearing or with
the second such gearing, the resulting speed
is fifteen or thirty kilometers (nine and three-
70 eighths or eighteen and three-fourths miles)
per hour, respectively. By using the reversed
motion two different speeds may be obtained
in the manner described.

In town, where the crowded traffic does not 75
allow riding at twenty kilometers per hour,
the first toothed gearing is always made use
of, generally in combination with the first set
of belts, the result being a speed of ten kilo-
meters per hour; but when higher speed is 80
desirable—for example, for overtaking an-
other car—the belt is changed, but not the
toothed gearing.

If it is a question of riding in the country
on flat ground, the second gearing is used, 85
while on hilly ground it is better to use the
first toothed gearing. The variations of speed
within the limits of each set of toothed gear-
ing are dependent on the different belts em-
ployed. By this arrangement I avoid the ne-
90 cessity of frequently altering the various gear-
ings.

An example of the improved construction
is shown in the accompanying illustrations,
drawn to different scales. By reference to 95
these drawings my invention will be more
fully understood.

Figure 1 represents the plan of the im-
proved mechanism. Fig. 2 is a rear view of
the same; Fig. 3, a lateral view, while Fig. 4, 100
on a smaller scale than Figs. 1, 2, and 3,
shows in a diagrammatic perspective view the
arrangement for governing the improved
mechanism for altering speed. Fig. 5 illus-

trates a detail. Fig. 6 is a vertical section along the vertical axis of Fig. 5. Fig. 7 is an outside elevation of Fig. 5 viewed from the left. Fig. 8 is a plan, partly in section, on a larger scale of Fig. 7. Fig. 9 shows two methods of connecting the rack c^2 to the rod c^3 .

Referring to the drawings, 1 is the rear axle of the car. It carries at its center part the usual box for the differential gear 2, this latter having a toothed rim 3 and, according to the specimen in the drawings, a brake-pulley 4. The axle 1 rotates in the interior of the tubes 7 and 8, to which are attached plates or flanges 5 and 6, between which the differential gear and its dependencies are located. The plates are spaced apart by sleeves 9 to the rear of the differential gearing. The space between the two plates is somewhat wider and serves for the reception of the gearing by means of which the reduction of speed is effected. The rear portions of the plates form bearings for four shafts, the first shaft 10, carrying the pinion 11, always engaging the toothed rim 3 of the differential gear 2 and further carrying the pinions 12 and 13 for two different speeds (forward driving) and the pinion 14 for the alteration of speed in the reversing motion. It must be well understood that these various pinions are mounted upon shaft 10 and are independent of and separated from the pinion 11. The second shaft 15 projects beyond the plates on each side and carries outside the latter, on each side, respectively, loose pulleys 16 and 17 and fixed pulleys 18 and 19, which pulleys are driven by means of belts from the motor. Between the two flanges the shaft 15 is of square section 20, and upon this part a sleeve 21, carrying two gears 22 and 23, is arranged with freedom to slide. The third shaft 27 is below the shaft 15 and carries a gear 26, which meshes with the gear 14. A fork 24, engaging a neck 25 of the sleeve 21, serves for displacing this latter upon the part 20 for the purpose of effecting the engagement between 22 and 12 or that between 23 and 13 for forward driving, or finally that between 23 and 14 through the medium of gear 26 on the intermediate shaft 27 for the reversing motion. The fourth shaft 28 is placed a little above shaft 15 and carries a sliding sleeve 29, provided with the fork 24.

In their normal positions the belts are maintained upon the loose pulleys by means of the forks 30 and 31, which are pivoted to collars 32 and 33, mounted upon the tubes 7 and 8. The arc described by the rear extremity of the forks 30 and 31 and its movement are limited at both ends by abutments 34, each forming one piece with the collars 32 and 33, respectively. The front extremities of the forks 30 and 31 are connected together by a spring 34^a, which exerts a constant tendency to keep the belts upon the loose pulleys.

The front end of each of the forks 30 and 31 carries a pin 35 and 36, respectively, en-

gaging in the slots 37 and 38, respectively, of a rigid rod 39, which is capable of moving from left to right, and vice versa.

In case, for example, the belt is to be put upon the fixed pulley 18, it suffices to push the rod 39 from the left to the right side. The fork 31 will remain stationary, because the pin 36 is able to slide in slot 38 when the rod 39 moves to the right, while the pin 35 is directly pushed to the right, and by its motion causes the belt to be displaced from the pulley 16 to pulley 18. When the rod 39 is moved from the right to the left side, the belt is put upon the fixed pulley 19.

In Fig. 4 the appliance for governing the forks 30 and 31 and the sleeve 29 is represented in a perspective view. The whole appliance is worked by a single element in connection with the steering-gear.

The steering of the car is effected by means of a hand-wheel a , which causes the bar b to turn, this latter acting upon the front wheels of the car by means of suitable connecting devices.

The controller proper for altering the speed of the car consists in a handle-bar c , capable of being actuated in two different ways. The first is a rotary motion around its own axis, by which motion the sleeve 29 may be displaced, and consequently an alteration of the gearing is effected. For this purpose the handle-bar c is provided with a pinion c' , meshing with a rack c^2 on the end of a rod c^3 , connected to the end of a crank c^4 on a shaft c^5 , situated upon the frame of the car. The rear extremity of this shaft c^5 carries a crank c^6 , extending in a downward direction, the end of which is connected by a swivel-joint and pivot to a rod c^7 , connected with the sleeve 29, this latter being designed for changing the speed by displacing the train of speed-reducing gear. By turning the handle of the bar c , and consequently the pinion c' , the rack c^2 is caused to ascend or to descend, the rod c^3 and the crank c^4 being compelled to follow this movement, but in moving crank c^4 causes the shaft c^5 to rotate, and as a result of this rotation the sleeve 29 is caused to move from left to right by means of the crank c^6 and the rod c^7 . The second motion which is communicated to the handle-bar c is effected in a plane at right angles to the tube d around the axis of this latter, as the bar c is mounted in a support made in one piece with the tube d , which surrounds the central rod b . The bottom end of the tube d carries a crank d' , connected by means of the rod d^2 with a crank d^3 , mounted on one of the extremities of tube d^4 , through which passes the shaft c^5 , its other extremity carrying crank d^5 , which extends in a downward direction. This latter crank d^5 is linked at the lower end to a rod d^6 , which is connected by means of a smaller rod d^7 with the slotted connecting-rod 39. It will easily be understood that by turning the tube d by means

of the handle *c* a reciprocating motion of the rod 39 from right to left, and vice versa, is caused.

In the detail represented by Fig. 5 it may be seen that the handle *c* carries a pawl *m*, engaging with one of the three notches of a fixed sector *m'* in such a manner that the revolution of the handle *c* around the axle *d* is limited at each position taken by the belt, 10 either upon the pulley 19 or upon pulley 18 or upon both of them.

As clearly shown on Fig. 6 the support or frame of the steering-gear is composed of a tube *r*, fixed in any convenient manner to the frame of the vehicle. The rod *b*, carrying the steering-wheel *a*, passes through said tube and is suitably connected at its lower end with the front wheels of the vehicle, as hereinbefore described. The supporting-tube *r* is surrounded by another tube *d*, carried and able to turn on the bottom collar *r'* of the tube *r*. Tube *d* is held and guided at the top by a cap *r''*, fixed to the supporting-tube *r*. The said cap carries a quadrant *m'*, rigidly 20 connected thereto. The top of the tube *d* is fitted with a casing *n*, in which the toothed wheel *c'*, the rack *c''*, the shaft and handle *c*, and the spring *q* are lodged. The shaft *c*, supported at *o* and *o'*, is held in position longitudinally by the spring *q*, which bears at one end on the washer *n'*, fixed to the casing, and at the other on a collar *p* on the shaft *c*. By means of a slotted keyway the shaft *c* can slide in the toothed wheel *c'* without affecting the rotatory movement of the latter when the handle is turned. A little beyond the spring, at the opposite end of the toothed wheel, the shaft *c* has a groove *p'*, into which enters a vertical stud, fixed to the catch *m*. 30 One end of the said catch latches into the notches on the quadrant *m'*, and the other pivots on a pin *n''*, fixed to the casing *n*.

The working of the arrangement is as follows: When a change of speed by means of the movable toothed gear is wanted, the handle of the shaft *c* is turned. This turns the toothed wheel *c'* and raises or lowers the rack *c''*, &c., as before described. The second movement of the shaft *c*—that is, at right angles to the shaft *d*—takes place as follows; the parts being supposed to be in the position shown on Fig. 8: When the handle of the shaft *c* is pulled in the direction indicated by the arrow, the said shaft compresses the spring *q* and, acting by its groove *p'* on the stud of the catch *m*, unlatches the latter from the notch of the quadrant *m'*. When this happens, the tube *d* can be rotated in either direction and the change of speed produced 40 by the shifting of the belts on the pulleys. The moment this is accomplished the shaft *c* by means of the spring *q* automatically latches the catch *m* into another of the three notches of the quadrant *m'*. The connection

of the rack *c''* to the rod *c''* can be made either 55 by a simple hook *u* on the rod *c''*, passed through a hole in end of rack *c''*, or by means of an ordinary joint with a pin, Fig. 9. The slight torsional strain on rod *c''*, produced by the very limited rotatory movement of the 70 tube *d*, may be neglected on account of the length of the said rod, the play in the joints, and from the fact that the rack is very near the center of rotation.

In the whole I claim as my invention and 75 as my exclusive property—

1. In a mechanism for altering speed, the combination with a driven shaft provided with a gear, of a driving-shaft provided with a plurality of independent belt-driving mechanisms of different speeds, an intermediate shaft provided with a gear meshing with the gear on the driven shaft, a plurality of different-speed gears on the driving and the intermediate shafts, means to bring either of said 85 belt mechanisms into operation, and means to bring either of said speed-gears into operation, substantially as set forth.

2. In a mechanism for changing speed, the combination with a driven shaft or axle provided with a gear, of a driving-shaft provided with a plurality of independent belt-driving mechanisms of different speeds, an intermediate shaft provided with a gear meshing with the gear on the driven shaft, a plurality 90 of different-speed gears on the intermediate shaft, a sleeve slidably mounted on the driving-shaft and rotatable therewith, different-speed gears carried by the sleeve, means to move the sleeve to bring either of its gears 95 into mesh with its respective gear on the intermediate shaft, and means to bring either of said belt mechanisms into operation, substantially as set forth.

3. In a mechanism for altering speed, the combination with a driving and a driven shaft, of a plurality of independent belt-driving mechanisms of different speeds mounted on the driving-shaft, a plurality of different-speed gears between the driving and driven shafts, a controlling device movable in two directions transverse to each other, and two series of connections between the controlling device and the belt-driving mechanisms and the speed-varying gears, whereby the movement of the controlling device in one direction will control the belt-driving mechanisms, and its movement in a transverse direction will control the speed-varying gears, substantially as set forth. 105 110 115

In testimony that I claim the foregoing as my invention I have signed my name in presence of two subscribing witnesses.

JOSEPH CHARLES EUGÉNE MATHIEU.
